CLAIM

The ornamental design for a display screen or portion
thereof with a set of graphical user interfaces, as shown and
described.

DESCRIPTION

The patent or application file contains at least one drawing
executed in color. Copies of this patent or patent application
publication with color drawing(s) will be provided by the
Office upon request and payment of the necessary fee.

FIG. 1 is a front view of a display screen or portion thereof
with a set of graphical user interfaces showing the claimed
design; and,

FIG. 2 is a second embodiment thereof.

The broken lines in the figures show a display screen or
portion thereof, and form no part of the claimed design.
The graphical user interface sets of the figures are arranged
relatively on the drawing sheet for the convenience of
illustration and their relative positioning forms no part of the
claimed design.
